UNITED STATES PATENT OFFICE.

GEORGE H. HUENERGARDT AND WILLIAM H. HUENERGARDT, OF COLLEGEVIEW,
NEBRASKA.

TOP FOR WASHING-MACHINES.

1,099,049.

Specification of Letters Patent.

Patented June 2, 1914.

Application filed September 29, 1913. Serial No. 792,452.

To all whom it may concern:

Be it known that we, GEORGE H. HUENERGARDT and WILLIAM H. HUENERGARDT, subjects of the Czar of Russia, residing at Collegeview, in the county of Lancaster, State of Nebraska, have invented a new and useful Top for Washing-Machines, of which the following is a specification.

This invention relates to tops for washing machines of that type shown for example in Patent No. 832,062, issued to George H. Huenergardt on October 2, 1906. In machines of this character a substantially semi-cylindrical tub is employed, the same being mounted for oscillation and having a top onto which water drained from a wringer is adapted to flow.

One of the objects of the present invention is to provide an all metal top which can be applied readily to the tub of a washing machine and which is provided with improved means for directing the drained water back into the tub through the opening in the top.

25 A further object is to provide a top which can be easily pressed from sheet metal, thus materially reducing the cost of production.

A further object is to provide a novel form of closure for the top opening, said 30 closure having yielding means for holding it in either open or closed position.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown.

45 In said drawings:—Figure 1 is a plan view of the top constituting the present invention. Fig. 2 is a side elevation thereof. Fig. 3 is a section on line A—B Fig. 1. Fig. 4 is a section on line C—D Fig. 1. Fig. 5 is a section on line E—F Fig. 1.

50 Referring to the figures by characters of reference 1 designates the body of the top, the same being formed of sheet metal and having upstanding sides 2 from which are extended exterior depending flanges 3, these flanges and sides coöperating to form an

exterior channel 4 adapted to receive the walls of the tub to which the said top is applied so that the top can be secured to the walls by means of rivets or the like extended through the sides 2 and into the walls. 60

The body 1 is provided with a centrally disposed depression 5 preferably substantially rectangular but with rounded corners, the said depression extending around an opening 6, the walls of the opening being 65 formed by the inwardly extending portions of the depression which are folded downwardly and backwardly, as shown at 7' in Fig. 4 to thus provide a rigid ledge for supporting a closure. Another elongated depression 7 is formed within the body 1 along one side thereof and is intersected by the deeper depression 5, this longer or receiving depression 7 being bounded along one side by one of the upstanding sides 2 while 75 its ends, and portions of its other side are bounded by upstruck curved ribs 8. Obviously by providing this depression 7 discharging into the central deeper depression 5, any water drained into the depression 7 80 will flow into the other depression and thus be directed through opening 6 into the tub. Reinforcing strips of sheet metal or the like are extended across the ends of the body 1, as shown at 9 and are soldered or otherwise 85 secured upon the upstanding sides 2, there being straps 10 interposed between these strips 9 and the body 1 for the purpose of bracing the strips 9 at their centers and permitting them to be used as handholds when 90 it is desired to lift the machine.

Secured upon the body 1 adjacent one side of the opening 6 is a strip 11 having upstanding terminal ears 12, there being an incision 13 within the strip adjacent its 95 center and whereby a strap 14 is formed, this strap being pressed upwardly so as to engage an eye 15 formed at one end of a coiled spring 16. Strip 11 is secured to the top 1 by means of rivets or the like and 100 the upstanding terminals 12 are pivotally connected to angular arms 17 normally extended over the opening 6 and thence downwardly, as shown at 18, these arms having terminals 20 riveted or otherwise fastened 105 upon a sheet metal closure 21. The terminals 20 are formed integral with an arched intermediate portion 22 constituting a handle, it thus being seen that both this handle and the two arms 17 are formed in a single 110

length of metal. Spring 16 is not only secured to the strip 11 in the manner hereinbefore described, but is also secured to a cross strip 23 connecting the arms 17 close to the downwardly extending portions 18. Closure 21, as hereinbefore stated, is formed of sheet metal and has its side portions folded inwardly to form outstanding flanges 24 from which depend aprons 25 designed to extend through the opening 6, the lower edges of the aprons being folded upwardly as shown at 26 to reinforce the aprons. These aprons are shaped so as to converge downwardly. Thus it will be seen that when the flanges 24 are resting on the ledges 6, the aprons 25 will fit snugly in the opening. Furthermore it will be seen by referring to Fig. 4, that when the closure is in shut position, spring 16 pulls downwardly along a line extending under the pivots of the arms 17. Thus the spring acts to hold the closure securely in shut position. When the closure is swung upwardly and laterally to open position, this spring also operates to hold the closure open.

It will be seen that the entire structure can be formed readily of sheet metal and thus the cost of producing a top for a washing machine is materially reduced.

It will be understood that by providing the elongated shallow depression 7, the water drained from the fabrics passing through a wringer will flow into this depression and thence into the deeper depression 5 so that, when the closure 21 is out of shut position, the water will thus be free to drain back into the tub.

By providing the strips 9, any water which may be thrown onto the top will be prevented from flowing over the ends of the top.

What is claimed is:—

1. A top for washing machine tubs, the same being formed of sheet metal having a depression provided with an opening in the bottom thereof, said depression constituting a closure seat, there being an additional elongated depression along one side of the top and discharging into the first named depression.

2. A top for washing machine tubs, the same being formed of sheet metal and having a depression provided with an opening in the bottom thereof, there being another shallow depression along one side portion of the top and discharging into the first named depression, a closure normally seated in the first named depression, arms secured

thereto and pivotally connected to the top beyond one side of the depression, and a spring connected to said top and to the arms and constituting means for holding the closure yieldingly in open or closed position.

3. A top for the tub of a washing machine, the same being formed of sheet metal and having upstanding sides, a depression, there being an opening in the bottom of the depression surrounded by a closure supporting ledge, and a shallow depression along one side of the body and discharging into the first named depression, said shallow depression being partly bounded by one of the upstanding walls and by upwardly extending ribs, a closure normally seated in the first named depression, arms secured thereto and pivotally connected to the top, said closure being adapted to swing into and out of the depressions.

4. The combination with a closure having a depression therein and an opening in the bottom of the depression, of a sheet metal closure having an annular flange adapted to rest upon the bottom of the depression, there being an apron depending from the closure for extending through the opening, a single strip of metal bent to form an upstanding intermediate portion or handle and parallel arms, said arms being secured to the closure, a strip secured upon the top adjacent the closure and having upstanding terminals pivotally engaged by the respective arms, a cross strip connecting the arms, and a spring secured at its ends to said cross strip and to the strip upon the top, said spring constituting means for holding the closure in either open or closed position.

5. A top for washing machine tubs, the same being formed of sheet metal having a depression provided with an opening in the bottom thereof, said depression constituting a closure seat, there being an additional elongated depression along one side of the top and discharging into the first named depression, and cross strips secured to the sides of the top at the ends thereof and constituting water retaining means.

In testimony that we claim the foregoing as our own, we have hereto affixed our signatures in the presence of two witnesses.

GEORGE H. HUENERGARDT.
WILLIAM H. HUENERGARDT.
